UNITED STATES PATENT OFFICE.

WILLIAM F. KELLETT, OF CHICAGO, ILLINOIS.

DESIGN FOR A PLASTER CENTER-PIECE.

SPECIFICATION forming part of Design No. 14,259, dated September 4, 1883.

Application filed December 1, 1882. Term of patent 14 years.

To all whom it may concern:

Be it known that I, WILLIAM F. KELLETT, a citizen of the United States, residing at Chicago, in the county of Cook and State of Illinois, have invented and produced a new and original Design for Plaster Center-Pieces for Rooms, of which the following is a true and correct specification, reference being had to the accompanying engraving, in which the figure shows my design with the molded frame, having panels ornamented as hereinafter described, such frame being surrounded with triangular panels, crescent-shaped border for corners, and Gothic pointed arch.

The accompanying engraving fully shows my design, which consists of a square molded frame, A, with ornamented corners and center blocks, and having a circular seed, F, in the center. Said frame incloses four square panels arranged alternately in half-rosette and husk, with leaves and tendrils (designated in the engraving as B) and wild rose and leaves, conventional, (marked C,) as shown in said figure. This molded frame is surrounded by triangular panels G, with Gothic leaves, with a crescent-shaped border, H, at the corner of said frame, and with wings consisting of Gothic pointed arch I of stems and banded leaves and V-shaped panel with billet-molding and scroll-work, as shown in said figure. The triangular panels, or crescent-shaped border, or Gothic

pointed arch, or all of said parts of my design, may be omitted whenever it may be thought proper from any cause whatever to do so.

I claim—

1. A plaster center-piece consisting of a square molded frame, A, containing circular seed in the center, and panels composed of half-rosette, husk, and tendril B, wild rose and leaves C, arranged alternately, said frame being surrounded by triangular panel G, with Gothic leaves, and said frame having crescent-shaped border H for corners, and Gothic pointed arch with V-shaped panels, all substantially as shown and described. 35

2. A square molded frame, A, having circular seed F in the center, and inclosing four panels arranged alternately in half-rosette and husk B, and wild rose and leaves, conventional, C, substantially as shown and described. 40

3. The triangular panel G, with Gothic leaves, substantially as specified. 45

4. The border H, substantially as shown.

5. The Gothic pointed arch I, with stems and banded leaves and V-shaped panel, with billet-molding and scroll-work, substantially as described. 50 55

WILLIAM F. KELLETT.
